UNITED STATES PATENT OFFICE.

GEORGE M. HOWELL, OF PATERSON, NEW JERSEY.

DESIGN FOR AN UPPER FOR SHOES.

46,906.

Specification for Design.

Patented Feb. 2, 1915.

Application filed October 3, 1914. Serial No. 864,963. Term of patent 7 years.

To all whom it may concern:

Be it known that I, GEORGE M. HOWELL, a citizen of the United States, residing at Paterson, in the county of Passaic and State of New Jersey, have invented a new, original, and ornamental Design for an Upper for Shoes, of which the following is a specification, reference being had to the accompanying drawing, forming part thereof.

Figure 1 is an elevation of the outside of

the shoe, and Fig. 2 is a like view of the inside of the same shoe.

I claim:

The ornamental design for an upper for shoes, as shown, irrespective of the type of heel.

GEORGE M. HOWELL.

Witnesses:

C. ZABRISKIE,
A. A. CARNEY.
